ELECTRICAL PLUG

Charles H. Stevens, Jr., Cornwall Bridge, Conn., assignor, by mesne assignments, to Whitney Blake Company, New Haven, Conn., a corporation of Connecticut

Application July 23, 1953, Serial No. 26,108

Term of patent 14 years

(Cl. D26—1)

To all whom it may concern:

Be it known that I, Charles H. Stevens, Jr., a citizen of the United States, residing at Cornwall Bridge, in the county of Litchfield and State of Connecticut, have invented a new, original, and ornamental Design for an Electrical Plug, of which the following is a specification, reference being had to the accompanying drawing, forming part thereof.

In the drawing:

Fig. 1 is a perspective view of the electrical plug, showing my new design;

Fig. 2 is a view similar to Fig. 1 showing the electrical plug in a slightly different perspective;

Fig. 3 is a front elevational view of the electrical plug.

The dominant features of my design reside in the portions shown in full lines.

I claim:

The ornamental design for an electrical plug, as shown and described.
